UNITED STATES PATENT OFFICE.

JOHN F. O'CONNOR, OF CHICAGO, ILLINOIS, ASSIGNOR, BY MESNE ASSIGNMENTS, TO
W. H. MINER, INC., A CORPORATION OF DELAWARE.

RESILIENT CONNECTER FOR MINE CARS.

Application filed September 4, 1923. Serial No. 660,726.

To all whom it may concern:

Be it known that I, JOHN F. O'CONNOR, a citizen of the United States, residing at Chicago, in the county of Cook and State 5 of Illinois, have invented a certain new and useful Improvement in Resilient Connecters for Mine Cars, of which the following is a full, clear, concise, and exact description, reference being had to the accompanying 10 drawings, forming a part of this specification.

This invention relates to improvements in resilient connecters for mine cars.

One object of the invention is to provide 15 a simple and relatively inexpensive resilient connector or coupling, particularly adapted for mine cars.

A more specific object of the invention is to provide a connector of the character 20 indicated, comprising a resilient loop pivotally secured to one end of a mine car adapted to be detachably connected to the adjacent end of another car, wherein the loop is adapted to yield to absorb the shocks in 25 both buff and draft.

Other objects and advantages of the invention will more clearly appear from the description and claims hereinafter following.

30 In the drawing forming a part of this specification, Figure 1 is a vertical, longitudinal, sectional view of the adjacent ends of two mine cars, showing my improvements in connection therewith. Fig. 2 is a top 35 plan view of the structure illustrated in Fig. 1. And Fig. 3 is a view similar to Fig. 1, illustrating a different embodiment of the invention.

In said drawing, referring first to the 40 construction illustrated in Figures 1 and 2, each mine car is shown as provided with a suitable heavy flooring 10 and a vertical end wall 11, the flooring 10 being cut away to provide a pocket, as indicated at 12 to 45 better accommodate the connecting or coupling members. At the opposite ends, each car is also provided with a drawbar 13. Each drawbar is in the form of an elongated flat plate extending through the end wall 50 11 and secured at its inner end to the flooring 10. Adjacent the outer end, each drawbar is provided with a downwardly projecting lug 14 abutting the end of the flooring 10. A bolt 15 extending through 55 the drawbar, the outer end of the floor 10

and a transversely extending reinforcing member 16 at the lower side of the wall, is preferably provided to secure the outer end of the drawbar to the car.

The resilient connecting or coupling 60 means proper, as shown in Figures 1 and 2, preferably comprises a spring loop A, and two blocks B and C swiveled to the respective drawbars of the two adjacent cars.

The spring loop A comprises two members 65 17 and 18, each consisting of a pair of spaced apart parallel arms 19—19 and a ring shaped section 20. Each of the loop members 17 and 18 is preferably formed from a flat bar of spring steel bent to 70 proper shape and tempered. The loop member 18 is preferably of such a size as to fit snugly within the loop member 17, thereby forming, in effect, a single connecting member. Although the spring loop A 75 is herein shown as composed of two members, it will be evident that the same may comprise one member only or may be made of a plurality of such members.

The blocks B and C are each provided 80 with a centrally disposed, upwardly projecting, cylindrical stem 21, and the projecting end of each drawbar is provided with an opening 22 adapted to receive the stem of one of the blocks. The stem of 85 each block serves to swivelly connect the same to the corresponding drawbar, the block being suspended below the drawbar by the stem 21 which projects above the drawbar and has a collar 23 fixed to the upper end thereof, bearing on the upper surface of the drawbar. The collar 23 is 90 preferably secured to the stem by a pin 24 extending therethrough and having the opposite ends thereof upset to retain it in 95 position. Each of the blocks B and C is thus swivelly supported, with the upper face thereof in contact with the under surface of the corresponding drawbar. To provide proper clearance so that the blocks 100 B and C will have free swinging movement, each of the same is formed with a curved face 25 adjacent the lug 14 of the corresponding drawbar 13.

The block C is preferably connected to 105 the drawbar at the gate end of the car, and the block B to the drawbar at the opposite end of the car, and the cars are so disposed when coupled that the block B on the end of one car is disposed in 110

opposed relation to the block C of the adjacent car.

The block B is cut away at opposite sides, thereby providing a tongue 26 to which 5 the loop A is pivotally connected by means of a horizontally disposed bolt 27 extending through the parallel arms 19 at the open side of the loop, the arms 19 being disposed on opposite sides of the tongue 26. The 10 loop is thus mounted for swinging movement in a vertical plane, and may be dropped out of the way to the dotted line position shown in Figure 1 to provide proper clearance when the car is in a restricted space, 15 as when the same is being handled on the mine hoist.

The block C is extended outwardly beyond the end of the drawbar 13 at the gate end of the car and is cut away as indicated 20 at 27, thereby providing a transversely curved slot and an upwardly extending hook member 28. The slot 27 is correspondingly curved to the ring section of the loop A and is of slightly greater width than the 25 thickness of the loop so as to freely accommodate the same, and the inner side of the hook member 28 at the upper end thereof is rounded off to properly guide the loop into the slot 27 when the same is engaged 30 with the hook member.

In draft action, it is evident that, as the cars are pulled apart the spring loop A, being fixed at one end to the block B and having the opposite end held by the hook member 28 of the block C, will be elongated, thereby absorbing the shocks. In a buffing action, as the cars approach each other, the 35 loop will be compressed against the rear wall of the slot 27, thereby elongating the 40 loop transversely.

Referring next to the embodiment of the invention illustrated in Figure 3, 110 indicates the floor of each mine car, 111, the 45 end wall and 113 the drawbar. The drawbars 113 are in all respects similar to the drawbars illustrated in Figures 1 and 2, each being provided with a downwardly extending lug 114 abutting the end of the flooring 110, and fixed to the car by means of a 50 bolt 115 extending through the drawbar, flooring 110 and a reinforcing member 116.

The resilient connecting or coupling means illustrated in Figure 3 comprises, broadly, a spring ring member A' and a pair of blocks B' and C'.

The member A' is in the form of a continuous ring formed of spring steel, properly tempered. The ring A' is pivotally connected to the block B', extending through an 60 eye member 130 at the upper end of the block. Below the eye 130, the block B' is provided with an annular flange 131 abutting the upper surface of the corresponding drawbar 113. The member B' is also provided with a downwardly extending, cylind-

rical stem 132 extending through an opening 133 formed in the outer end of the drawbar. A collar 134 fixed to the lower end of the stem 133 by a transversely extending pin 135 serves to retain the block B' on the 70 drawbar 113, the block being thus swivelly mounted. The block C' is swiveled on the drawbar 113 at the gate end of the car in a manner similar to the block B', the stem 132 thereof extending through the opening 75 133 in the drawbar, being held in position by the collar 134 secured by the pin 135. The block C' is directly supported by the drawbar 113, the lower face of the former being in abutment with the upper surface of 80 the drawbar. The block C' is also provided with an upwardly opening, transversely extending slot 127 similar to the slot 27 shown in Figures 1 and 2 and adapted to receive 85 the free end of the ring member A'.

It will be evident that the ring A' may be swung out of the way in a manner similar to the loop A of the construction shown in Figures 1 and 2, the width of the drawbar 113 to which the block B' is attached being 90 such that the ring will clear the same when in its lowermost position with the bar extending into the ring.

The operation of the form shown in Figure 3 is in all respects similar to that previously described, the ring A' being elongated longitudinally in draft and being compressed and elongated transversely in buff.

I have herein shown and described what I now consider to be the preferred manner 100 of carrying out my invention, but the same is merely illustrative, and I contemplate all changes and modifications that come within the scope of the claims appended hereto.

I claim:

1. In a connector for mine cars, the combination with a resilient loop; of means for connecting the same to two adjacent cars, comprising a block to which one end of the loop is pivotally connected, and a hook member coacting with the other end of the loop, said block being attached to one of said cars and the hook being attached to the car.

2. In a connector for mine cars, the combination with a spring loop; of means for connecting said loop to two adjacent cars, comprising a block to which one end of the loop is pivotally connected and a hook coacting with the other end of the loop, said block and hook being swiveled to the respective cars.

3. In a device of the character described, the combination with a spring loop coupling; of means for connecting the loop to two adjacent cars, said loop being adapted to yield to absorb the shocks in both buff and draft.

4. In a device of the character described, the combination with a yielding loop having one end thereof pivotally connected to one

end of a car; of means for detachably connecting the opposite end of the loop to the adjacent end of another car, said means abutting the loop interiorly and exteriorly.

5 5. In a connector for mine cars, the combination with a coupling including an elastic ring shaped section; of means for attaching said coupling to the adjacent ends of two cars.

10 6. In a connector for mine cars, the combination with an elastic coupling having a bowed section; of means for permanently attaching the same to one car; and means for detachably connecting said coupling to an-

15 other car, said means abutting the inner and outer sides of said section.

7. In a device of the character described,

the combination with a coupling including a spring ring member; of a block swiveled to one end of a mine car; means for pivotally connecting said coupling to said block to swing in a vertical direction; and a block swiveled to the adjacent end of another car, said block being provided with a slot within which a section of said ring is adapted to engage to couple said cars. 20 25

In witness that I claim the foregoing I have hereunto subscribed my name this 1st day of September, 1923.

JOHN F. O'CONNOR.
